UNITED STATES PATENT OFFICE.

JACOB M. ROTH, OF PITTSBURGH, PENNSYLVANIA.

CASTING-MOLD.

1,199,427.

Specification of Letters Patent. Patented Sept. 26, 1916.

Application filed November 24, 1915. Serial No. 63,171.

To all whom it may concern:

Be it known that I, JACOB M. ROTH, a citizen of the United States, residing at Pittsburgh, in the county of Allegheny and State of Pennsylvania, have invented certain new and useful Improvements in Casting-Molds, of which the following is a specification, reference being had to the accompanying drawings.

- 10 This invention relates to molds of the character described in my application for patent filed March 27, 1915, Serial No. 17,486, molds of this character being used in the process of welding a metal lining of 15 one character upon a metal core of a different character, the composite billet so formed being subsequently drawn, fashioned or shaped into various commercial articles.
- 20 In the carrying forward of the process as described in my prior application above referred to, a steel core is disposed within a mold body larger than the core so as to provide a space around the core and molten 25 copper is afterward introduced into the mold to fill up the space around the steel core and become welded thereto.

It is one of the objects of my present invention to provide means permitting the expansion of the steel core when it is surrounded by the molten copper and at the same time provide means for preventing the specific gravity of the molten copper from floating or raising the steel core relative 35 to the copper which surrounds it.

A further object of the invention is to provide a cap piece so formed as to center the steel core and hold it centered, but which will permit the pouring of the molten copper into the space around the steel core and which will rise with the expansion of the steel core or billet.

A further object of the invention is to provide in connection with a mold a base of 45 graphite or like refractory material which will support and center the lower end of the core or steel billet and which, when the molten metal is poured into the mold, is so formed as to permit the molten metal to pass beneath the base and thus cause the base and core to move upward together under the action of the specific gravity of the molten copper.

Still another object of the invention is the 55 provision in connection with a mold of

the character described and a cap of the character described, a removable head section so formed as to permit the upward movement of the cap for a limited distance under the expansion of the core or billet 60 through the action of the heat of the molten copper.

Other objects will appear in the course of the following description.

My invention is illustrated in the accompanying drawings wherein:

Figure 1 is a vertical section of a mold constructed in accordance with one form of my invention and showing the head piece therein partly in section; Fig. 2 is a fragmentary section taken on a plane at right angles to the plane of Fig. 1; Fig. 3 is a top plan view of the construction shown in Fig. 1; Fig. 4 is a vertical sectional view of another form of my invention, the head piece and base being in section; Fig. 5 is a top plan view of the construction shown in Fig. 4; Fig. 6 is a sectional view of the lower end of the mold shown in Fig. 4 but showing the manner in which the base and 75 core are raised by flotation; Fig. 7 is a vertical sectional view of another form of my invention, the head piece being partly broken away; Fig. 8 is a sectional view of a mold showing a core being lowered thereinto; Fig. 9 is a like view to Fig. 8 but showing the core in a lowered position and a head piece applied thereto.

One form of my invention is illustrated in Figs. 1 to 3 wherein 10 designates the body section of the mold which may be made of any suitable material, such as cast iron, steel, carborundum or alundum. The mold is shown as being cylindrical in form and as having its bottom formed with a circular 90 recess 11 which is concentric to the axis of the mold. The side wall of the mold is formed at diametrically opposite points with vertically extending slots 12. Disposed within the body 10 and having sliding engagement at its ends with the wall of the body is a head piece or cap 13 whose form is illustrated in Fig. 3. This head piece or cap is oblong in form and has rounded ends 14 which engage the inside face of the wall 105 of the cap for sliding movement. The upper face of the cap 13 is upwardly and centrally inclined from the ends toward the middle, as at 15, and at its middle there is provided the upwardly extending lug 16 which 110

has a width less than that of the cap 13. This cap 13 or head piece is formed of fire clay or like material and the lug 16 is of such a height that when the cap or head piece is in place upon a steel core A the upper end of the lug will be disposed in line with the lower edges of the vertical slots 12. The under face of the head piece 13 is formed with a seat 17 on the upper end of the core A, this seat of course being concentric to the axis of the mold. When the core A is disposed within the mold and the head piece 13 is disposed upon the upper end of the core, a bar 18 of graphite is disposed through the slots 12 and rests upon the upper end of the lug 16. With this construction, when molten metal is poured into the mold, it will flow downward into the space between the core A and the mold itself. The heat of the mold will cause the core A to expand longitudinally, thus carrying the head piece 13, which constitutes a follower, upward and carrying the bar 18 upward until the bar 18 engages with the upper ends of the slots 12. The head piece or cap 13 and the bar 18 have a certain predetermined weight, which, bearing against the upper end of the core A, prevents the core rising or attempting to float as it otherwise would do because of the difference between the specific gravity of the molten copper and the specific gravity of the core A. The head piece 13 and the bar 18 permit the core to expand however until the bar 18 engages the upper ends of the slots 12 as before stated.

It is to be noted that the inclined upper faces 15 of the head piece or follower 13 direct the molten metal into the annular space surrounding the core A and prevent metal collecting upon or pouring being precluded by the member 13. Molten metal is poured into the upper end of the mold at one point on its diameter and the air contained within the space between the core and the mold will pass out at an opposite point on the diameter of the mold. As the metal collects or rises in the body of the mold the air and gases are expelled therefrom and thus there is an uninterrupted flow of the molten metal into the mold and all possibility of the formation of air-holes or blow-holes in the metal precluded. The composite rod or billet is now removed from the mold and the clay head piece or follower broken off. This composite rod or billet will then be rolled and drawn for manufacture into various commercial articles.

In Figs. 4, 5 and 6, I show another form of mold adapted to attain the same ends as the mold illustrated in Fig. 1. In these figures 18 designates a mold body of the same character as the mold body which I previously described only this mold body is not formed with a recess in its bottom.

Disposed within the mold body and resting upon the bottom of the mold is a base 19 of graphite or like refractory material. This base is formed at its center with a recess 20 which is concentric to the mold and in its periphery the base is formed with a plurality of vertically disposed grooves 21. The core A, which may be of steel or other suitable material of like character, is disposed within the recess 20 or seat and then a head piece 22 is placed within the mold, this head being recessed upon its under face as at 23 to receive the upper end of the core. This head has the same form as that illustrated in Fig. 1, except that it is not provided with the upwardly extending lug 16 but is formed with the centrally inclined upper faces 24 whereby to direct molten metal into the space between the core and the wall of the mold. With this construction the molten metal is poured into the mold in the manner heretofore described and fills the space between the core and the mold and it also flows down by way of the grooves 21 into the space between the base 19 and the bottom of the mold. Inasmuch as the head piece 22 can rise, the core A can expand, but as the molten copper flows down beneath the base 19, the base 19, the core A and the head piece 24 will rise together through the mold body 18 and under the action of the difference between the specific gravity of the copper and the specific gravity of the core and the members 19 and 22. (See Fig. 6.)

While in the form of my invention illustrated in Figs. 1 to 3 I prevent or resist any elevation of the core by the weight of the head piece 13 and bar 18, in Fig. 4 I do not resist this tendency of the core to rise but provide means whereby the base upon which the core rests and the head piece shall rise with the core. The head piece 22, however, by reason of its weight, will, to a certain extent, resist the tendency to rise. After the molten metal and the space surrounding the core has cooled and solidified the composite billet may be withdrawn from the mold and the base and head piece crushed, broken, or otherwise cut away so as to provide the billet having a core of steel or other ferrous metal and a covering or lining of non-ferrous metal, such as copper.

In Fig. 7 I show a slightly different construction from that shown in Fig. 1. In this case the mold, which is designated 25, has a core seat 26 in its bottom to support the core A. The mold 25 is of a height less than that of the core. Adapted to be disposed upon the upper end of the mold is a head section 27 which tapers upward slightly and whose lower end is formed with the outwardly and downwardly projecting annular flange 28 which engages snugly over the upper end of the mold. Any suitable pack-

ing material may be disposed between the upper end of the mold and the lower end of the head section 27. The inner face of the head section 27 is annularly recessed at 29 5 at the lower end of the head section, this recess terminating at its upper end in a shoulder 30. Disposed within this head section 27 and resting upon the core A at the time that the article is to be formed is a 10 head piece or follower 31 recessed upon its under face to form a seat 33 which centers the upper end of the core A, the upper face of this head piece 31 being laterally and downwardly inclined, as at 34, from a 15 middle point, the purpose being, as before explained, to prevent the collection of the molten metal upon the upper face of the head piece and direct the molten metal into the space between the core and the wall of 20 the mold. With the construction above described the expansion of the core is permitted by the fact that the head piece 31 is supported within the annular recess 29 so that it may rise therein until it strikes 25 against the shoulder 30 when its further upward movement is prevented. In this case the annular head section 27 acts as a weight preventing the upward movement of the core and of the head piece 31 due to the difference in the specific gravity of the core and 30 the molten metal surrounding it. In this case also after the molten metal surrounding the core is solidified, the core is withdrawn and the head piece 31 is broken off.

35 In Fig. 8 I show still another application of my invention, wherein 85 designates a mold having a recess 86 at its lower end. In this case the lower portion of the mold is intended to be filled with molten copper or 40 like metal, designated B, there being, of course, an air space above the molten metal. The core A is then inserted into the mold until it rests at its lower end in the seat 86. The core may be supported by means of a 45 magnet C while it is being inserted, though I do not wish to limit myself to this, and the entrance of the core into the molten metal displaces the molten metal and causes it to rise within the member 85 until it fills the 50 mold. When the core has been disposed in its seat the cap piece 37 is placed in the top of the mold and over the core, this cap piece being approximately rectangular in form and having rounded ends fitting against the 55 wall of the mold and having a seat 88 upon its under face concentric to the mold which receives the upper end of the core and centers it. This cap piece is of course broken off, crushed or otherwise disposed of 60 when the composite billet is withdrawn from the mold. This cap piece 37 is also formed with the inclined upper faces in the manner heretofore described and the cap piece rises as the core A expands.

65 It will be understood that in all of the

different forms of my invention the cap pieces 13, 22, 31 and 37 are formed of clay or like material.

I have found that by the use of the means illustrated I secure a layer or lining of copper which extends a uniform distance along the core and does not extend around in immediate contact with the lower end of the core which would otherwise be the case, due to the floating of the core with relation to the relatively heavy molten copper. By this means, therefore, I secure a more thorough union between the core and the molten copper.

A very important function of the member 18 in Fig. 1 and of the shoulder 30 in Fig. 7 is that if the core A floats upward it cannot float out of the molten metal, nor can it escape at its lower end from the seats 11 and 26, respectively. Thus the core is held 85 centered at all times even though it does float upward to a slight degree. The same is true of the construction shown in Fig. 4. Here, though the core may float to some extent yet it will always be centered because 90 the base 19 will float with the core. If the core is not centered it is obvious that it would be liable to take a position out of alinement with the axis of the mold and thus the coating or lining of copper around the 95 exterior of the core would not be uniform in thickness. The same is true of the construction shown in Figs. 8 and 9 wherein the cap piece 37 can move upward to a limited degree but not a sufficient amount to 100 permit the core to escape from the seat 36 by reason of the use of the pouring spout 27 which is exactly the same as the member 27 illustrated in Fig. 7 and previously described. In all forms of my invention, therefore, I have provided means for preventing the core from floating out of the centering device to thus secure a uniform thickness of metal around the core.

Having described my invention, what I 110 claim is:

1. A mold including a body having a core seat and being open at its upper end, and a head piece having a core seat on its under face and having sliding engagement with the upper end of the mold body, the extent of movement of the head piece with relation to the mold body being limited in a direction toward the open end of the mold.

2. A mold including a body having a core 120 seat at its lower end and being open at its upper end, and a head piece having a core seat on its under face and having sliding engagement with the upper end of the mold body, said head piece having upwardly and 125 medially inclined faces.

3. A mold including a body closed at its lower end and having a core seat in said end and being open at its opposite end, a head piece having limited sliding engagement in 130

the mold and in the body and having a core seat on its under face, said head extending partly across the diameter of the mold whereby to leave a pouring opening, the depth of 5 the first-named seat being greater than the amount of movement possible for the said head piece.

4. A mold including a body having a core seat at its lower end and being open at its 10 upper end, and a head piece disposed within the body and having a core seat upon its under face, the head piece being freely movable through the body, said head piece being substantially rectangular in form and having 15 its upper surface inclined upwardly and medially.

5. A mold of the character described including a body having a core seat at its lower end and open at its upper end, a head 20 piece vertically movable within the body and having a core seat on its under face, said head piece being rectangular in plan and having a width less than the diameter of the body and having an upwardly and 25 medially inclined upper surface.

6. A mold including a body having a core seat at its lower end and open at its upper end, a head piece having a core seat on its under face and disposed in said mold for 30 free vertical movement, and means for limiting the upward movement of the head piece.

7. A mold including a body having a core seat in its lower end and having an opening 35 at its upper end, and a head piece disposed within the mold for vertical movement and

having a core seat on its under face, said head piece having a weight tending to resist flotation of the core under the action of molten metal disposed within the mold 40 and surrounding the core.

8. A mold including a body having a core seat in its lower end and having an opening at its upper end, a head piece disposed within the mold for vertical movement and having a core seat on its under face, said head piece having a weight tending to resist flotation of the core under the action of molten metal disposed within the mold and surrounding the core, and means permitting 50 limited upward movement of the head piece under the expansion of the core.

9. The combination with a mold, of means for centering a core within the mold and holding it centered at all times upon the 55 upward flotation of the core when fluid metal is disposed around it.

10. The combination with a mold having a core centering seat at its lower end and adapted to support a core concentrically 60 within the mold, of a core centering member within the mold engaging with the upper end of the core and movable therewith for a limited distance to permit expansion of the core, the depth of the first-named seat 65 being greater than the amount of movement possible for the upper core centering member.

In testimony whereof I hereunto affix my signature.

JACOB M. ROTH.
